UNITED STATES PATENT OFFICE

WILLIAM A. COOPER, OF KOKOMO, INDIANA, ASSIGNOR TO GLOBE AMERICAN CORPORATION, OF KOKOMO, INDIANA, A CORPORATION OF INDIANA

DESIGN FOR A RANGE

Application filed May 3, 1930. Serial No. 35,490. Term of patent 14 years.

To all whom it may concern:

Be it known that I, WILLIAM A. COOPER, a citizen of the United States, residing at Kokomo, in the county of Howard, State of Indiana, have invented a new, original, and ornamental Design for a Range, of which the following is a specification, reference being had to the accompanying drawing, forming part hereof.

The figure is a perspective view of a range, showing my new design.

I claim:

The ornamental design for a range, as shown.

WILLIAM A. COOPER.
